UNITED STATES PATENT OFFICE.

LOWRY LEWIS, OF PEMBERTON, WEST VIRGINIA, ASSIGNOR OF ONE-HALF TO
STEPHEN HARNISBERGER, OF WARRENTON, VIRGINIA.

BOTTLE CASE OR CONTAINER.

1,408,751.

Specification of Letters Patent.

Patented Mar. 7, 1922.

Application filed February 3, 1921. Serial No. 442,220.

To all whom it may concern:

Be it known that I, LOWRY LEWIS, a citizen of the United States, residing at Pemberton, in the county of Raleigh and State 5 of West Virginia, have invented certain new and useful Improvements in Bottle Cases or Containers, of which the following is a specification, reference being had thereto in to the accompanying drawings.

10 This invention relates to a bottle case or container or more specifically to a shipping crate or container.

The object of the invention is the construction of a simple and efficient shipping 15 case or container in which any broken parts can be quickly replaced or repaired.

Another object of the invention is the construction of a shipping case or bottle container which will efficiently retain the bottles 20 or receptacles in a spaced relation, and which container has its spacing or separating means held in place by comparatively thin, transverse strips held against the top dividing strips of the container.

25 With these and other objects in view, my invention comprises certain novel combinations, constructions and arrangements of parts as will be hereinafter described, illustrated in the accompanying drawings, and 30 more particularly pointed out in the appended claims.

In the drawings:

Figure 1 is a perspective view of a shipping container constructed in accordance 35 with the present invention, a portion of the top being broken away to show part of the interior of the container.

Figure 2 is a sectional view, taken on line 2—2, Fig. 1, and looking in the direction 40 of the arrows.

Figure 3 is a section, taken on line 3—3, Fig. 2, and looking in the direction of the arrows.

Figure 4 is a fragmentary, perspective 45 view of another embodiment of the present invention.

Referring to the drawings by numerals, 1 designates the body of the container in the sides 2 of which are formed vertical 50 slots 3, and in the ends 4 are formed vertical slots 5.

Hand holes 6 are formed in the ends 4 near their tops or upper edges.

Transverse dividing and spacing strips 7

are placed in the vertical slots 3, while longitudinally-extending dividing strips 8 are placed in the slots 5. I preferably place a 55 number of transverse strips 7, first, in the body 1, (Fig. 2), and then a series of longitudinally-extending strips 8 in the body 60 against the top of the strips 7, then a set of strips 7 are placed in the body against the top of strips 8, and against these last-mentioned strips 7, I place a set of strips 8.

To hold the transverse and longitudinally-extending strips securely within the body 1, I employ, preferably, two flexible strips 9, which strips 9 are placed directly over the hand holes 6 (Figs. 2 and 3), against the top edges of the upper longitudinally-extending strips 8. In the embodiment shown in Figs. 1 and 2, the flexible strips enter, at their ends, small notches or pockets 10 in the sides 2 of the body 1, whereas, in the embodiment shown in Fig. 4, the flexible 75 strip 9^a is held in place against the top edges of the strips 8 by suitable fastening means, such as screws 11. Either of the strips 9 or 9^a will serve to retain all of the dividing and spacing strips 7 and 8 in their assembled 80 position within the body of the container.

The principal advantage of placing the securing strips 9 and 9^a in alignment with the hand holes 6 resides in the fact that the operator can use his fingers or a tool, as represented at 12, (Fig. 3), to push the retaining strip, or strips, out of the pockets 10, or away from the ends 4, as in Fig. 4, to permit the strips 9 or 9^a to be quickly removed from the body of the container to 90 allow the strips 7 and 8 to be removed when desired, as in the case where a strip, as for instance, when a strip is broken and one has to be substituted therefor. Further, the hand holes 6 furnish efficient means for enabling the operator to lift or carry the case, by the fingers or the hands being inserted into these holes 6. Therefore, it will be seen that there is a true combination between the strips 9 and 9^a, for the holes perform 95 two functions, as to permit the operator to grip the case, and, second, to allow the operator to more quickly remove the strips from their engaging position against the ends of the container when it is desired to remove 105 the dividing strips therein.

A suitable top or cover 13 is placed upon the body 1.

My shipping crate or container is comparatively inexpensive in construction, and entering into this inexpensive structure is the efficient way of retaining the dividing strips within the body, to wit: the flexible retaining strips that extend across the ends of the container, bearing against the top dividing strips, holding all of the spacing and dividing strips snugly together.

10 While I have described the preferred embodiments of my invention, and have illustrated the same in the accompanying drawings, certain minor changes or alterations may appear to one skilled in the art to 15 which this invention relates, during the extensive manufacture of the same and I therefore, reserve the right to make such alterations or changes as shall fairly fall within the scope of the appended claims.

20 What I claim is:

1. In a device of the class described, the combination of a body provided with sides and ends, said ends provided with hand holes, partitioning means in said body, and 25 retaining strips engaging the partitioning

means and positioned over the inner ends of the hand holes within the body.

2. In a device of the class described, the combination of a body provided with hand holes, partitioning means in said body, retaining strips in the body and engaging the partitioning means and positioned directly over the inner ends of the hand holes, and means at the inner ends of the retaining strips for fastening the strips against accidental displacement within the body. 35

3. In a device of the class described, the combination of a body provided with sides and ends, said ends provided with hand-holes, said sides provided with pockets at 40 their ends in alignment with the hand holes, partitioning means in said body below the hand holes, and flexible securing strips in the body against the partitioning means positioned over the hand holes and having 45 their ends in the pockets of the sides, substantially as shown and described.

In testimony whereof I hereunto affix my signature.

LOWRY LEWIS.
